US00D692391S

(12) **United States Design Patent**
Kim

(10) **Patent No.:** **US D692,391 S**
(45) **Date of Patent:** **** Oct. 29, 2013**

(54) **O-RING**

(75) Inventor: **Jin-Kwang Kim, Kyung-Nam (KR)**

(73) Assignee: **Tyco Electronics Amp Korea Ltd.,**
Kyungsangbuk-Do (KR)

(**) Term: **14 Years**

(21) Appl. No.: **29/399,840**

(22) Filed: **Aug. 19, 2011**

(30) **Foreign Application Priority Data**

Feb. 21, 2011 (KR) 30-2011-0006799

(51) **LOC (9) Cl.** **13-03**

(52) **U.S. Cl.**

USPC **D13/154; D23/269**

(58) **Field of Classification Search**

USPC D13/133, 147, 148, 154, 184, 199;
D23/259, 262, 269; 174/31.5, 50.52,
174/59, 60, 64, 520, 539, 554, 650;
277/301, 304, 310-311, 351, 902-935;
439/180, 246, 252, 278, 374, 378, 379,
439/380, 381, 527, 530, 533, 892, 894

See application file for complete search history.

(57) **CLAIM**

The ornamental design for an O-ring, as shown and described.

DESCRIPTION

FIG. 1 is a top perspective view of an O-ring, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a cross sectional view thereof taken along the line 8-8 of FIG. 6.
